ABSTRACT

Apparatus for generating a signal from an electrical instrument includes two transistor amplifiers adapted to receive electrical signals from a transducer in the vicinity of the vibrations from the instrument. The amplified signal is applied to an oscillator which includes a radiating element to frequency modulate the oscillator signal with the amplified signal. The oscillator signal is radiated, detected, amplified, and reproduced by a nearby fm radio.

APPARATUS FOR TRANSMITTING THE OUTPUT OF A MUSICAL INSTRUMENT FOR AMPLIFICATION

BACKGROUND OF THE INVENTION

1. Field of the Invention

This invention relates to circuits for use with musical instruments, and more particularly to a circuit for transmitting the output of a musical instrument for amplification.

2. Description of the Prior Art

Of current popularity for use with musical instruments, and particularly for use with guitars and similar such stringed instruments, are amplifier systems to which the vibrations of the instrument, transduced into electrical signals, are applied. Many commercially available guitars, for example, include a pickup head or similar transducer physically built into the guitar adjacent the strings upon soundbox to facilitate such amplifier connection.

The amplifiers and speaker systems available for use with such musical instruments are ordinarily intended for the single purpose of receiving electrical signals for one or more guitars or other such instruments for amplification and sound distribution. Additionally, ordinarily the guitars are necessarily physically connected to the amplifiers used by a cord, which limits the freedom of movement of the player or which requires the players keeping track of the cord and moving from place to place.

SUMMARY OF THE INVENTION

In light of the above, it is, therefore, an object of the invention to provide a portable unit for use with a musical instrument for transmitting the musical vibrations thereof to a nearby radio for detection and amplification.

It is another object of the invention to provide a portable vibration transmitting circuit for use with a guitar having an electrical pickup head to obviate the necessity of connection to an amplifier.

It is still another object of the invention to provide a transistorized unit which is portable and can be carried upon the musical instrument for transmitting the vibrations thereof to a nearby radio for detection and amplification.

It is yet another object of the invention to provide an electrical circuit which can be mounted onto and carried by a guitar to generate a frequency modulated signal of the electrical signal of the guitar pickup and for radiating the signal through the air to a nearby fm receiver for detection and amplification.

These and other objects, features, and advantages will become apparent to those skilled in the art from the following detailed description when read in conjunction with the accompanying drawings and claims.

The invention, in its broad aspect, presents a portable transmitting unit for use with a musical instrument, such as a guitar or the like, which includes means for connection to a vibration detecting electrical transducer in the vicinity of the musical instrument. Means are provided for amplifying the electrical signal of the transducer, and an oscillator means is provided having an oscillation signal, the frequency of which is within the frequency detection range of a nearby radio. Means are included for applying the amplified electrical signal

to the oscillator to modulate the oscillator signal with the amplified electrical signal, and the frequency modulated signal is applied to a radiating means included in the oscillator for radiating the modulated signal into the air to be thereby reproduced by the nearby radio.

BRIEF DESCRIPTION OF THE DRAWING

The invention is illustrated in the accompanying drawing in which the sole figure illustrates an electrical schematic diagram of the circuit, in accordance with the invention, for use in generating a frequency modulated signal from a guitar for detection, amplification and reproduction by a nearby fm radio.

DETAILED DESCRIPTION OF THE PREFERRED EMBODIMENTS

The apparatus, illustrated in the accompanying drawing, includes a circuit, generally denoted by the reference numeral 10, for producing a signal frequency modulated by a signal representing the musical vibrations of a musical instrument, such as a guitar 11. The frequency modulated signal is detected by a nearby fm radio 12 and therein amplified and applied to a speaker 13 to be reproduced. In particular, the musical vibrations from the guitar 11 transduced into electrical signals by a guitar pickup 15 mounted on the guitar in a manner well known in the art are then conducted by wires 17 for connection to the circuit 10 by a plug or other electrical connection means, denoted generally by the arrows 19 and 20.

The circuit 10 includes three general sections or stages, first and second amplifier sections 25 and 26, respectively, (ordinarily since the electrical output from transducers commonly used with musical instruments is at a relatively low level, at least two amplification stages are preferably employed to bring the signal to a suitable level for transmission) and an oscillator section 27. The first amplifier stage 25 includes a transistor 30 of p-n-p conductivity type, to the base of which the signal from the pickup 15 is applied via a coupling capacitor 31. Resistors 36 and 37 are provided to the emitter and collector, respectively, for biasing and loading the transistor 30.

The second amplifier stage 26 includes a transistor 35 of p-n-p conductivity type to the emitter of which the input signal from the pickup 15 is applied by a resistor 33. The signal developed at the collector of the transistor 30 is conducted by line 40 to the base of the transistor 35, and the signal developed across the emitter resistor 36 of the first amplifier stage transistor 30 is coupled by a capacitor 41 in series with the parallel combination of a resistor 42 and capacitor 43 to the collector of the second amplifier stage transistor 35. Resistors 45 and 46 are provided, respectively, to the emitter and collector of the transistor 35 for biasing and loading it, and a bypass capacitor 48 is provided in parallel with the emitter resistor 45 to isolate the transistor 35 from the rf signal developed by the oscillator section 27, below described.

The signal developed at the collector of the transistor 35 is coupled by a coupling capacitor 50 to the base of a third p-n-p conductivity type transistor 55 which forms an oscillator circuit. A voltage divider including resistors 56 and 57 properly maintains the potential of the base of the transistor 55 with respect to the other transistor elements, and a capacitor 58 provides a by-

pass path in parallel with the resistor 57. The collector of the transistor 55 is connected to a frequency determining tank circuit including a capacitor 60 and a variable inductor 61, the variable inductor 61 functioning as the radiating element from the oscillator section 27. If desired, an additional signal radiating element (not shown) can be coupled to the variable inductor 61, such as by a tap or by other well known manners, to increase the range of signal transmission. A capacitor 62 interconnects the collector and emitter to effect the frequency modulation of the oscillator signal with the amplified guitar pickup signal, and a biasing resistor 64 is provided in connection with the emitter of the transistor 55.

Finally, a battery 65 provides the source of electrical energy to the first two amplifier stages 25 and 26 and the oscillator stage 27, and a capacitor 66 is connected in parallel with the battery 65 to isolate it from the alternating currents encountered in the circuit 10.

By way of example, specific components which can be used in the circuit 10 are as follows:

Transistors

30 — ECG102A
35 — ECG102A
55 — ECG160

Resistors

33 — 68K ohms
36 — 330 ohms
37 — 30K ohms
42 — 15K ohms
45 — 1,000 ohms
46 — 10K ohms
56 — 15K ohms
57 — 5K ohms
64 — 1,000 ohms

Capacitors

31 — 5. mfd
41 — 0.02 mfd
43 — 0.005 mfd
48 — 0.30 mfd
50 — 5. mfd
58 — 0.001 mfd
60 — 12. mfd
62 — 3. mfd
66 — 82. mfd

It should be noted that although the circuit 10 has been illustrated and described as including transistors of p-n-p conductivity type, transistors of other conductivity type can be equally advantageously employed with appropriate changes in power supply, polarity, biasing, and so forth, as will be apparent to those skilled in the art.

In operation, the vibrations from the guitar pickup 15 are coupled by the capacitor 31 and the resistor 33 to the respective base and emitter of the first and second amplifier stage transistors 30 and 35. The signal at the first amplifier stage transistor is also coupled directly by line 40 to the base and through the capacitor 41 and capacitor 43 - resistor 42 network to the emitter of the second stage transistor 35. The output signal of the second stage transistor 35 is applied to the base of the oscillator transistor 55 to frequency modulate the oscillation signal thereof.

The oscillation signal is radiated by the inductor 61 to be received by an antenna 70 of a nearby fm radio or tuner 12. The received signal is then amplified by the amplifier of the radio, or an amplifier in conjunction with the tuner, and applied to a speaker 13.

Since the signal radiated from the inductor 61 is within the range of detection of an fm radio, the inductor 61 is preferably variable to enable the oscillation signal to be changed in the event that the signal is detected on the same frequency as, for example, a commercial radio station in the particular locality which the circuit 10 is used. Thus, in such event, the inductor 61 can be tuned to a frequency within the fm frequency band in the particular locality at which no preexisting signals exist.

The circuit described thus enables a guitar or like musical instrument to be operated without requirement for expensive amplification systems for the sole use of the individual instrument. The instrument, when used 20 in connection with the circuit 10, can be used with a preexisting fm radio or hi-fidelity system to take advantage of the amplifiers of such a system in place of the specific amplifier for the guitar or such instrument.

Furthermore, the circuit 10 can easily be fabricated 25 on a printed circuit board, or other miniaturized electronic assembly, and can be made conveniently as small as practical. This facilitates mounting the circuit 10 upon the instrument, for example, concealed within the soundbox of the guitar 11.

30 Although the invention has been described and illustrated with a certain degree of particularity, it is understood that the present disclosure is made only by way of example and that numerous changes in the combination and arrangement of parts may be resorted to without departing from the spirit and scope of the invention 35 as hereinafter claimed.

What is claimed is:

1. A portable transmitting unit for use with a musical instrument comprising: a vibration detecting electrical 40 transducer mounted on said instrument; a first amplifier stage including a first transistor of p-n-p conductivity type, a first capacitor connected between said transducer and the base of said first transistor, a first bias resistor connected between ground and the emitter of said first transistor, a source of d.c. energy one side of which is connected to ground, a second bias resistor connected between the ungrounded side of said source of d.c. energy and the collector of said first transistor; a second amplifier stage including a second transistor of the p-n-p conductivity type, a first coupling resistor connected between the base of said first transistor and the emitter of said second transistor, a second capacitor connected at one side to the emitter of said first transistor, a third capacitor and a second coupling resistor connected in parallel, the parallel connection of said second coupling resistor and said third capacitor being connected between the other side of said second capacitor and the collector of said second transistor, means directly connecting the collector of said first transistor to the base of said second transistor, a third bias resistor connected between ground and the emitter of said second transistor, a fourth capacitor connected in parallel across said third bias resistor and constituting an r-f bypass for said second transistor, a fourth bias resistor connected between the collector of said second transistor and the ungrounded side of said source of d.c. energy; an oscillator and transmitter stage includ- 45 50 55 60 65

ing a third transistor of the p-n-p conductivity type, a fifth bias resistor connected between the ungrounded side of said source of d.c. energy and the base of said third transistor, a sixth bias resistor connected between ground and the base of said third transistor, a fifth capacitor connected in parallel across said sixth bias resistor, a sixth capacitor connected between the collector of said second transistor and the base of said third transistor, a seventh bias resistor connected between ground and the emitter of said third transistor, a tank circuit consisting of a seventh capacitor and a variable inductor connected in parallel and connected between the ungrounded side of said source of d.c. energy and the collector of said third transistor, said tank circuit functioning to cause said oscillator and transmitter

15

stage to provide an oscillation signal the frequency of which is within the frequency reception band of a nearby f-m radio receiver, said variable inductor also constituting a radiating means for radiating said oscillation signal into the air, an eighth capacitor connected between the collector and emitter of said third transistor to effect frequency modulation of said oscillation signal with the amplified signal from said transducer; a ninth capacitor connected in parallel across said source of d.c. energy and constituting an a.c. bypass for said source of d.c. energy; whereby the radiated oscillation signal is detected and the vibrations of said musical instrument are reproduced and amplified by said f-m radio receiver.
